UNITED STATES PATENT OFFICE.

COLOMAN ROZÁR, OF NUREMBERG, GERMANY.

KEYBOARD FOR TYPE-SETTING MACHINES.

SPECIFICATION forming part of Letters Patent No. 719,375, dated January 27, 1903.

Application filed December 21, 1901. Serial No. 86,757. (No model.)

To all whom it may concern:

Be it known that I, COLOMAN ROZÁR, a subject of the Emperor of Austria-Hungary, residing at Nuremberg, Germany, have invented 5 a new and useful Keyboard Device for Type-Setting Machines, of which the following is a specification.

This invention relates to an improved keyboard for type-setting machines of all kinds 10 and other similar apparatus, the characteristic feature of which device consists in the fact that the operations or manipulations to be effected by means of the said keyboard can only take place after the key which has been 15 acted upon has been released. The advantage of this arrangement is that when the keyboard is employed with linotype-machines, for example, the same letter is not repeatedly set when the key which has been struck is 20 not released quickly enough. If my improved keyboard device is employed in conjunction with a punching appliance for the registering-strips for automatically-acting composing-machines, for instance, owing to the fact 25 that the movement of the apparatus required in order to effect the punching operation is only commenced or prepared for by the depression of the key, the said movement taking place only when the key again rises, the 30 same punching effect cannot be repeatedly produced by one and the same depression of a key, however long such depression may be continued.

A constructional form of my improved keyboard device is represented in the accompanying drawings, in which—

Figure 1 is a sectional view through a keyboard embodying this invention in the condition of repose, and Figs. 2, 3, and 4 are sectional views of the same in the different positions.

When depressed, each key 1 acts upon an anchor-lever 3, rotatably mounted upon a shaft 2. This lever is maintained raised by 45 means of a spring 4. In the plane of each of these anchor-levers is rotatably mounted upon a shaft 5 a three-toothed locking-disk 6, which is submitted to the influence of a spring 7, which bears against the corresponding rod 9.

This rod 9 is also acted upon by a spring 10, in opposition to the action of the spring 7 and tending to draw the rod 9 toward a rock-

ing lever 11, the rods 9, which are provided with noses 12, being pivoted to the extremities of these levers 11. So long as the locking-disk 6 is retained in the position of rest (shown in Fig. 1) by the nose or hook 14 of the lever 3 resting upon the tooth 13 the influence of the spring 7 preponderates in such a manner that the arm or rod 9, with its nose 12, is 60 held out of the path of a rail 15, which is fixed upon a lever-frame 16, which latter is maintained constantly oscillating upon an axis 18 by means of a continuously-rotating shaft 17. This is still the case when the key 1, and with 65 it the anchor-lever 3, is depressed, Fig. 2, as the disk 6 merely rotates slightly until its tooth 19 comes into contact with the arm 20 of the lever 3. When the key 1 is released, Fig. 3, the spring 4 raises the lever 3. The locking-disk is 70 thus released and continues to rotate under the influence of the spring 7 until its tooth 13 bears against the transverse ledge 21, whereupon the tension of the spring 7 is diminished to such an extent that the spring 10 is able to 75 draw the arm 9, with its nose 12, into the path of the rail 15. When this latter next descends, it takes with it the arm 9 by engagement with the nose 12, Fig. 4. The extremity of the lever 11 then engages with the tooth 80 22 of the disk 6 and causes it to resume its initial position, so that the nose 14 is again in front of the tooth 13, and at the end of the ascending movement of the rail 15 the arm 9 is withdrawn from the path of the said rail by 85 means of the spring 7, which is again placed in tension. Each arm takes with it in its downward movement one of the levers 11 or actuates by means of a pin 23 a lever 24 or other part by means of which the displacements or manipulations of the device or machine which is for the time being connected up with the keyboard apparatus is effected. 90

I claim—

1. In an apparatus of the character described, the combination with an actuating-lever, power devices, and a key, of means controlled by an adjustment of the key for connecting said lever and power devices after the key has been restored to its normal position. 95

2. In an apparatus of the character described, the combination of an actuating-lever, power devices, means adapted to connect 100

said lever and power devices, a locking device normally holding said connecting means in inactive position, a key adapted to be adjusted to withdraw the locking device from engagement with said connecting means, and means for preventing connection of the lever and power devices until the key is restored to its normal position.

3. In an apparatus of the character described, the combination of an actuating-lever, power devices, means adapted to connect said lever and power devices, a locking device normally holding said connecting means in inactive position, a key adapted to be adjusted to withdraw the locking device from engagement with said connecting means, and a stop controlled by movement of the key for preventing connection of the lever and power devices until the key is restored to its normal position.

4. In an apparatus of the character described, the combination of an actuating-lever, power devices, spring-actuated means adapted to connect said lever and power devices, means for normally holding said connecting means in inactive position, an adjustable key, and means controlled by said key for intermittently releasing and engaging said connecting means during each movement of the key, whereby the lever and power devices will not be connected until the movement of the key has been completed and it is in its normal, inactive, position.

5. In an apparatus of the character described, the combination of an actuating-lever, power devices, means adapted to connect said lever and power devices, a locking device normally holding said connecting means in inactive position, a stop for said connecting means, and an adjustable key adapted at each operation to successively release said lock and move said stop to and from engagement with said connecting means, whereby the lever and power devices will not be connected until the movement of the key is completed.

6. In an apparatus of the character described, the combination of an actuating-lever, power devices, a pivotally-mounted rod adapted to connect said lever and power devices, a revolute disk mounted at one side of and connected with said rod, a key-lever normally engaging said disk and holding the connecting-rod in an inactive position, a key connected with and adapted when depressed to disengage the key-lever from said disk, to permit the connecting-rod to move toward its operative position, and a stop adapted to be adjusted into position to engage said disk as the key is depressed and before the connecting-rod reaches its operative position to prevent connection of the lever and power devices until the key is restored to its normal, inactive position.

65 7. In an apparatus of the character described, the combination of an actuating-lever, power devices, a swinging rod adapted to

connect said lever and power devices, a spring acting to move said rod into operative position, a key-lever having two stops and adapted to hold the connecting-rod out of operative position, and a key connected with said lever, said stops being so arranged that when the key is depressed one of them will be withdrawn and the other moved into operative position and as the key returns to its normal position the last said stop will be withdrawn from and the first said stop moved into operative position.

8. In an apparatus of the character described, the combination of an actuating-lever, power devices, a swinging rod adapted to connect the lever and power devices, a spring acting to move said rod into operative position, a key-lever, and two stops connected with and adapted to be adjusted by the movement of the swinging rod into and from engagement with the key-lever during each movement of said lever, for the purpose set forth.

9. In an apparatus of the character described, the combination of an actuating-lever, power devices, a swinging rod adapted to connect said lever and power devices, a spring acting to move said rod into operative position, a revolute disk connected with and adapted to be rotated by movement of the swinging rod, a key-lever normally engaging said disk and holding the swinging rod in an inoperative position, a key connected with said lever, a stop movable with the key and adapted to be adjusted thereby into position to limit the movement of said disk when the latter is released by the key-lever, said stop being withdrawn from its operative position as the key returns to its normal position, and means for returning the swinging rod and said disk to their normal positions.

10. In an apparatus of the character described, the combination of an actuating-lever, power devices, a swinging rod adapted to connect said lever and power devices, a spring acting to move the swinging rod into operative position, a revolute disk connected with and adapted to be rotated by movement of the swinging rod, a key-lever having a forked end, one member of which normally engages said disk and holds the swinging rod in an inoperative position, a key connected to said key-lever and adapted when depressed to rock the same to disengage the aforesaid member of the forked end thereof from said disk and to adjust the other member of said forked end into position to arrest the movement of said disk and swinging rod before the latter has reached its operative position, both members of said forked end of the key-lever being out of engagement with said disk as the key is restored to its normal position, and means for returning the swinging rod and revolute disk to their normal positions.

11. In a keyboard mechanism for composing-machines, the combination of a power device, a part to be operated, means for con-

necting said part with the power device, a stop normally holding said connecting means in an inoperative position, a key for withdrawing said stop, and means for preventing connection of the power device and part to be operated until said key is released.

12. In a keyboard mechanism for composing-machines, the combination of a power device, a part to be operated, means adapted to connect said part with the power device, a stop normally holding said connecting means in an inoperative position, a key for withdrawing said stop, and means, actuated by the key while withdrawing said stop, for preventing connection of the part to be operated and the power device until the key is released.

13. In a keyboard mechanism for composing-machines, the combination of a power device, a part to be operated, means adapted to connect said part with the power device, two stops each adapted to hold said connecting means in inoperative position, and a key adapted to successively withdraw said stops, the parts being so arranged as to prevent connection of the part to be operated and the power device until the key is released.

In testimony that I claim the foregoing as my invention I have signed my name in presence of two subscribing witnesses.

COLOMAN ROZÁR.
